[57] CLAIM

The ornamental design for an automobile tire, as shown
and described.

DESCRIPTION

FIG. 1 is a perspective view of an automobile tire showing
our new design, it being understood that the tread
pattern is repeated throughout the circumference of the
tire, the opposite side being substantially the same as
that shown;

FIG. 2 is an end elevational view thereof;

FIG. 3 is a side elevational view thereof;

FIG. 4 is an enlarged, fragmentary developmental plan
view thereof;

FIG. 5 is a cross-sectional view thereof taken about line
V—V of FIG. 4.
